(57) CLAIM

The ornamental design for a golf tee, as shown and described.

DESCRIPTION

FIG. 1 is a perspective view showing my new design;
FIG. 2 is a front elevational view thereof;
FIG. 3 is a rear elevational view thereof;
FIG. 4 is a left elevational view thereof;
FIG. 5 is a right elevational view thereof;
FIG. 6 is a top view thereof; and,
FIG. 7 is a bottom view thereof.
The dashed lines in the figures depict structure that forms no part of the claimed design. The dot dash lines in the figures depict boundaries of the claimed design and form no part of the claimed design.

1 Claim, 6 Drawing Sheets(56)
